UNITED STATES PATENT OFFICE.

JOHN JACOB KINZER, OF WILDWOOD, PENNSYLVANIA, ASSIGNOR TO PITTSBURG BRAKE SHOE COMPANY, OF PITTSBURGH, PENNSYLVANIA, A CORPORATION OF PENNSYLVANIA.

BRAKE-SHOE.

1,219,464.

Specification of Letters Patent. Patented Mar. 20, 1917.

Application filed December 30, 1915. Serial No. 69,379.

To all whom it may concern:

Be it known that I, JOHN JACOB KINZER, a citizen of the United States, and resident of Wildwood, in the county of Allegheny and State of Pennsylvania, have invented a new and useful Improvement in Brake-Shoes; and I do hereby declare the following to be a full, clear, and exact description thereof.

10 My invention relates to brake-shoes and has special reference to such class of shoes which are known as "filled shoes", and formed of separate backs having a filling such as a body of frictional material for engagement with a wheel in braking. Heretofore in the manufacture and use of this class of brake-shoes it was difficult to get an inclosing casing that would support the heavy brake pressures and also resist fracture from expansion and contraction caused by the frequent exposures to heat and cold when the brakes were applied and released. Another difficulty was on account of the body being cast to the back or casing in some cases, in which where it was desired to use such back again, it would require a great deal of labor to remove same without injuring such back and rendering the same useless.

30 The object of my invention is to overcome these difficulties or objections and provide a cheap, simple and efficient form of a brake-shoe which can be easily and quickly manufactured, assembled and taken apart, is so constructed that the body of the same will permit of the back being used again after the body is worn down, and will enable expansion and contraction in the shoe to the extent desired.

40 To these ends my invention consists, generally stated, in the novel arrangement, construction and combination of parts, as hereinafter more specifically set forth and described and particularly pointed out in the 45 claims.

To enable others skilled in the art to which my invention appertains to construct and use my improved brake-shoe, I will describe the same more fully referring to the 50 accompanying drawing, in which—

Figure 1 is a side elevation, partly in section, of my improved brake-shoe;

Fig. 2 is a back view of the same;

Fig. 3 is a face view of the same;

55 Fig. 4 is a cross section on the line 4—4

Fig. 1, looking in the direction of the arrow;

Fig. 5 is a perspective view of one of the intermediate blocks;

Fig. 6 is a sectional view showing another 60 form of the back member; and

Fig. 7 is a detail view showing another form of the invention.

Like symbols of reference herein indicate like parts in each of the figures of the drawing.

As illustrated in the drawing A represents my improved brake-shoe, which comprises the back member 1, the body or wheel engaging member 2, and the lug member 3, 70 which is adapted to connect the shoe to the ordinary approved brake-head or hanger (not shown).

The body member 2 is formed of a plurality of intermediate and end inclosing sections or blocks 4 and 5 respectively, which are formed of a material, such as cast iron or fiber, with the sections 4 being of I-beam shape and thus providing the end flanges 6 and the connecting webs 7 between the same. 75 The flanges 6 form the side walls of such body member 2 and with such webs 7 extending across and between such flanges will form the channel portions or recesses 8 in the sections or blocks 4 for inclosing and supporting the fillers 9, which are formed of a composition of material, well known in the art, and which is inserted in such recesses, as hereinafter described. The side edges of the flanges 6 and the sides of the webs 7 are 80 curved, on the same plane, as at 10 and 10', respectively, and are also tapered outward from the back member 1 and toward each other at their outer or front ends or faces, in order to form interlocking wedge-shaped 85 faces when in position in the shoe and in supporting the fillers 9, such edges of said flanges bearing against each other in the finished shoe.

The end inclosing sections or blocks 5 are 100 formed of a material, such as cast iron or fiber and are preferably solid and provided with seats 12 in the outer end walls 11 of the same, while the inner or opposite walls 13 of said blocks are curved and tapered to 105 conform with the side edges on the flanges 6 in forming the end recesses 8 for the fillers 9.

The back member 1 is formed of semi-elastic or ductile metal, such as steel, and is 110

provided with the back wall or strip 14 which is adapted to fit within seats 14' formed in the back of the webs 7 and end blocks 5. The back wall 14 has its ends formed with the usual short bearing surfaces 15, which are provided with the recesses 16 in the same and they are adapted to bear or abut against bearings on the ends of the brake-head or hanger. 5 The brake-head or hanger is also provided with the usual central or intermediate bearings which are adapted to abut against the back wall 14 on the back member 1 and on each side of the lug 3 connected to such wall 10 as hereinafter described. The back member 1 is also provided with the end portions 17, which extend down along the end walls 11 on the end blocks 5, and the ends 18 of such portions are turned in, so-as to fit within 15 the seats 12 in the end blocks 5 when the back member is attached to the body member 2 formed by the sections or blocks 4 and 5 and fillers 9 for clamping these parts in place, while such hooked portions will fit 20 against the end walls 11 on such blocks 5.

The supporting lug 3 can be connected to the shoe A in any suitable manner, but as shown, is separate from the back member and attached thereto. In such case the lug 30 3 is formed of metal, such as steel, and is provided with the supporting standards or legs 19, which are adapted to be passed through slots 20 in the back wall 14, so that the ends 21 on such legs can be bent under 35 such wall in order to fit within seats 22 and 22' formed in the fillers 9 and in the webs 7 respectively.

In forming my improved brake-shoe A, the back member 1 is cut to the shape and 40 size required, which forms the back wall or strip 14, which is afterward pressed or stamped to shape to form the bearing surfaces 15 with their recesses 16 and the hooked portions 17 and ends 18. The back 45 wall 14 is also punched to form the slots 20 in the same, and then the lug 3 is connected to said wall by passing the legs 19 through said slots and bending the ends 21 of the same under said wall. The inclosing sections or blocks 4 and 5, which are formed to the shape desired, are then placed on the back member 1, so that the wall 14 of such member will rest within the seats 14' in such blocks, and the ends 21 on the lugs 3 will fit 50 within the seats 22' in the webs 7, while the ends 18 on the hooked portions 17 will fit within the seats 12 in the blocks 5. Thus tapered spaces or openings will be formed between the curved and inclined faces 10 on 55 the flanges 6 of the blocks 4. The material for forming the fillers 9 can now be placed within the recesses 8 formed in the blocks 4 and 5 and between the webs 7 in the blocks 4 and such webs and the inner face 13 on 60 the blocks 5, and while the back member 1

and the blocks 4 are suitably supported, pressure is applied in any suitable manner and by any suitable means to such filling material to pack the same within the recesses 8. This filling material in thus forming the 70 fillers 9 will also pack itself around the bent ends 21 on the legs 19 of the lug 3 and thereby form the seats 22 in such fillers for such ends, and while the back member 1 and blocks 4 and 5 are thus held and supported, 75 suitable pressure can be applied to the inner or front ends of such blocks 4 and 5 and fillers 9, which will bind such back member and form the completed shoe by giving such back and blocks the proper curve for the 80 body member 2 to conform to the wheel. When the back member 1 and inclosing blocks 4 and 5 are so curved such blocks and fillers 9 will be pressed tightly together, so that the spaces or openings previously 85 formed between the edges 10 on the flanges 6 of said blocks will close and such edges bear against each other, while the material forming such fillers, being yielding, will further pack such fillers, and the end walls 90 11 on the blocks 5 will be drawn more tightly against the braked portions 17 on said back member, thereby clamping such blocks and fillers in said back member firmly and securely in place between the walls 14 95 and 17 on said back.

When it is desired to remove the blocks 4 and 5 and fillers 9 from the back member 1, in case the inclosing casing formed by such blocks and fillers is worn down, or for any 100 other cause, such as breakage, fracture, etc., the shoe A can be suitably supported and suitable pressure applied to the convex side of the same, which will thereby flatten out 105 the same and free the blocks 4 and 5 from each other and from the fillers 9, so that such sections or blocks and fillers can be easily and quickly removed from the back member.

If desired, the back wall 14 on the back 110 member 1 can be provided with a side lip or flange 23 for fitting down over the flanges 6 on the blocks 4 and over the blocks 5, as shown in Fig. 6, which will further assist in holding said blocks and fillers 9 in place 115 within said back member 1, while if desired, such fillers can be previously formed to the shape and ready for insertion in the recesses in such blocks, and the filling material may also be used in a plastic state. 120 The blocks 4 and 5 can be further interlocked by forming a rib 24 on one of the side edges 10 on their flanges 6 for fitting within a like shaped recess 25 on the opposite side edge of the adjacent flange, and 125 if desired the back member can be formed sufficiently resilient, so that it can be easily and quickly sprung onto and off the inclosing body member.

Various other modifications and changes 130

in the design and construction of my improved brake-shoe may be resorted to, without departing from the spirit of the invention or sacrificing any of its advantages.

5 It will be obvious that all the parts of my improved brake-shoe can be easily and quickly manufactured, assembled and taken apart, and the body member being capable of being readily removed by taking out the 10 sections or blocks composing the same, will enable the back member to be used over again for a number of times, thereby saving a great cost in the manufacture of these shoes. The shoe will also permit of expansion and contraction either when used in 15 braking or idle, and will thereby overcome liability to breakage or fracture, and working or twisting out of curvature, and thus allow for a full contact bearing on the wheel at all times. The shoe so designed 20 will give a higher efficiency in retarding the class of heavy high speed trains, than the ordinary class of these brake-shoes, and will enable material to be used which is best suited for braking on the wheel and which 25 heretofore has been prevented from being used by reason of liability to fracture and other causes.

It will also be obvious that the removal 30 of the body sections or blocks can be obtained without injury, fracturing or breaking such back member employed, so that such back member will be in absolutely good condition for instant use, and while the shoe 35 has all the advantages of lightness and capability of use on high speed trains, and especially on heavy steel cars with high brake pressure, it will be strong and durable, and will be able to withstand the ordinary and hard knocks and usage by reason of the clamping of the parts in place.

What I claim as my invention and desire to secure by Letters Patent is—

1. A brake-shoe comprising a supporting 45 member, a body member for engaging the wheel and formed of a plurality of inclosing sections or blocks having a filling of frictional material within the same, and means for locking said blocks.

50 2. A brake-shoe comprising a supporting member, a body member for engaging the wheel and formed of a plurality of inclosing sections or blocks having a filling of frictional material within the same, and 55 means on said blocks for locking the same.

3. A brake-shoe comprising a supporting member, a body member for engaging the wheel and formed of a plurality of inclosing sections or blocks having a filling of 60 frictional material within the same, said blocks having flange portions for forming the sides of said body member, and means on said flange portions for locking said blocks.

65 4. A brake-shoe comprising a supporting

member, a body member engaging the wheel and formed of a plurality of inclosing sections or blocks having a filling of frictional material within the same, said blocks having flange portions for forming the sides 70 of said body member, and means on the bearing faces on said flange portions to lock said blocks.

5. A brake-shoe comprising a supporting member, a body member for engaging the 75 wheel and formed of a plurality of inclosing sections or blocks having a filling of frictional material within the same, said blocks having wedge-shaped flanges for bearing against each other to lock said 80 blocks.

6. A brake-shoe comprising a supporting member, a body member for engaging the wheel and formed of a plurality of inclosing sections or blocks having a filling of 85 frictional material within the same, and curved tapering flanges on said blocks for bearing against each other to lock said blocks.

7. A brake-shoe comprising a supporting 90 member, a body member for engaging the wheel and formed of a plurality of inclosing sections or blocks having a filling of frictional material within the same, and curved tapering flanges at each end of said 95 blocks for bearing against each other to lock said blocks, said flanges having a lip at one side and a recess at the other side for receiving the lip of the flange of the adjacent block.

100 8. A brake-shoe comprising a supporting member, a body member for engaging the wheel formed of a plurality of inclosing sections or blocks provided with flange portions for forming the sides of said body 105 member, a wall between the said flange portions, fillings of frictional material between said portions and walls, and means for locking said blocks.

9. A brake-shoe comprising a supporting 110 member, a body member for engaging the wheel formed of a plurality of inclosing sections or blocks provided with flange bearing portions for forming the sides of said body member, walls between said flange portions, 115 fillings of frictional material between said portions and walls, and said walls and the bearing faces on said flanged portions being adapted to lock said blocks.

10. A brake-shoe comprising a supporting 120 member, a body member for engaging the wheel formed of a plurality of inclosing sections or blocks provided with flange bearing portions for forming the sides of said body member, and fillings of frictional material 125 between said blocks, said bearing portions being wedge-shaped thereby to lock said blocks.

11. A brake-shoe comprising a supporting 130 member, a body member for engaging the

- wheel formed of a plurality of inclosing sections or blocks provided with flange bearing portions for forming the sides of said body member, and fillings of frictional material between said blocks, said bearing portions being curved and tapered, thereby to lock said blocks. 16. A brake-shoe comprising a back member, a body member formed of a plurality of inclosing sections or blocks having a filling of frictional material within the same, the end blocks having a seat within the end walls of the same, and turned in portions on the ends of said back member for fitting within said seats to hold the blocks in place. 50
12. A brake-shoe comprising a supporting member, a body member for engaging the wheel formed of a plurality of inclosing sections or blocks provided with flange bearing portions at each end for forming the sides of said body member, and fillings of frictional material between said blocks, said bearing portions being wedge-shaped, thereby to lock said blocks, and said bearing portions each having a lip at one side and a recess at the other side for receiving the lip of the bearing portion of the adjacent lock. 17. A brake-shoe comprising a supporting member, a body member for engaging the wheel formed of a plurality of inclosing sections or blocks, said sections or blocks having recesses within the same, and a filling of frictional material within the recesses of adjacent blocks. 55
13. A brake-shoe comprising a back member, a body member for engaging the wheel formed of a plurality of inclosing sections or blocks having a filling of frictional material within the same, and means on the ends of said back for fitting within the end walls of the end blocks to hold the blocks in place. 18. A brake-shoe comprising a supporting member, a body member for engaging the wheel formed of a plurality of inclosing sections or blocks having recesses within the same, a filling of frictional material within the recesses of adjacent blocks, and means for locking said blocks. 60
14. A brake-shoe comprising a back-member, a body member formed of a plurality of inclosing sections or blocks having a filling of frictional material within the same, the end blocks having a seat within the end walls of the same, and turned in portions on the ends of said back member for fitting within said seats to hold the blocks in place. 19. A brake-shoe comprising a supporting member, a body member for engaging the wheel formed of a plurality of I-shaped sections or blocks to provide recesses on each side of the same, and a filling of frictional material within the recesses of adjacent blocks. 70
15. A brake-shoe comprising a back member, a body member for engaging the wheel formed of a plurality of inclosing sections or blocks having a filling of frictional material within the same, and means on the ends of said back for fitting within the end walls of the end blocks to hold the blocks in place. 20. A brake-shoe comprising a supporting member, a body member for engaging the wheel formed of a plurality of I-shaped sections or blocks to provide recesses on each side of the same, a filling of frictional material within the recesses of adjacent blocks, and means for locking said blocks. 75
- In testimony whereof, I the said JOHN JACOB KINZER, have hereunto set my hand. 80 JOHN JACOB KINZER.
